United States Patent Office

Des. 226,877

Patented May 8, 1973

226,877

POWER DRIVEN HAIR COMB

James E. Tucker, Chicago, Ill., assignor to
The Gillette Company, Boston, Mass.

Filed Apr. 10, 1972, Ser. No. 242,913

Term of patent 14 years

Int. Cl. D28—03

U.S. Cl. D86—8

FIG. 1 is a side elevational view of a power driven hair comb showing my new design;

FIG. 2 is a bottom plan view;

FIG. 3 is a top plan view;

FIG. 4 is an end elevational view taken from the right hand end of FIG. 1;

FIG. 5 is an end elevational view taken from the left hand end of FIG. 1.

I claim:

The ornamental design for a power driven hair comb, as shown.
